(57) CLAIM

The ornamental design for a bookmark with flashlight, substantially as shown and described.

DESCRIPTION

FIG. 1 is an isometric view from the front of a bookmark with flashlight incorporating the design;

FIG. 2 is a right-side view thereof;

FIG. 3 is a top plan view thereof;

FIG. 4 is a bottom plan view thereof;

FIG. 5 is a front view thereof; and,

FIG. 6 is a rear view thereof.

The structure depicted by means of broken lines in FIGS. 1 through 3 has been shown for illustrative purposes only and forms no part of the claimed design.
